FLARING TOOL YOKE

George E. Franck, Morton Grove, Ill., assignor to
Imperial-Eastman Corporation, a corporation of
Illinois

Filed July 22, 1963, Ser. No. 76,031

Term of patent 14 years

(Cl. D54—13)

FIGURE 1 is a front elevation of a flaring tool yoke showing my new design, the rear elevation being identical thereto;

FIGURE 2 is a righthand elevation thereof, the lefthand elevation being identical thereto;

FIGURE 3 is a top plan view of the yoke body and with the threaded element shown in cross section taken along the line 3—3 of FIGURE 1; and

FIGURE 4 is a bottom plan view thereof and with the threaded element shown in cross section taken along the line 4—4 of FIGURE 1.

The dominant features of the design reside in the portions shown in full lines.

I claim:

The ornamental design for a flaring tool yoke, as shown and described.
